UNITED STATES PATENT OFFICE.

FREDRICH J. RODE, OF CHICAGO, ILLINOIS, ASSIGNOR TO MARQUETTE TOOL & MFG. COMPANY, OF CHICAGO, ILLINOIS, A CORPORATION OF ILLINOIS.

HYDRAULIC CUSHION FOR METAL PRESSES.

Application filed April 18, 1927. Serial No. 184,603.

This invention relates to improvements in hydraulic cushions particularly adapted though not necessarily limited in its use in sheet metal presses in which the metal is shaped by means of cooperating dies, one of which dies is reciprocable toward and away from the other, the work being clamped or held by means of a blank or work holding element that co-operates with a reciprocable die member, the blank or work holding element being resisted in its movement in one direction by the said cushion, and one of the objects of the invention is to provide an improved hydraulic cushion of this character in which a predetermined quantity of liquid is used in the cushion, the cushion embodying cylinder and piston members, the liquid being circulated from one side to the other of the piston for establishing the resistance pressure and to the other side of the piston to permit the pressure to be relieved.

A further object is to provide improved means for restoring the blank or work holder to its normal position. To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a view in side elevation, partly broken away, partly in section and with parts omitted of a sheet metal press having an hydraulic cushion constructed in accordance with the principles of this invention applied thereto.

Figure 2 is an enlarged detail sectional view of the pressure controlling valve.

Figure 3 is a detail sectional view taken on line 3—3, Figure 2.

Referring more particularly to the drawing the numeral 10 designates generally the frame of a sheet metal press having a reciprocable ram 11 to which a die 12 is connected. The ram is reciprocable by means of a link 13 connected with a crank shaft 14, the latter being driven in any suitable manner (not shown).

Mounted upon the bed plate 15 of the machine is a die 16 with which a work or blank holding member 17 co-operates. The blank or work holding member 17 is supported by means of pins 18, which in turn pass loosely

through the bed plate 15 and are supported by means of a pressure pad or plate 19.

All of the above referred to parts are of the ordinary and well known construction.

Supported beneath the bed of the machine, 60 preferably in a pit 20, is a supporting member 21 held in position by means of suitable hangers 22 which are secured to a suitable fixed part of the machine.

Mounted upon the supporting member 20 65 is a cylinder 23 of any desired size and diameter and reciprocable in the cylinder is a piston 24, having a piston rod 25 which passes through a suitable packing 26 in the end of the cylinder and is secured in any suitable 70 manner such as by means of fastening devices 27 to the bottom of the pin plate or pad 19.

The pad or plate 19 is supported by means of bars or rods 28 constituting hangers. These bars 28 are secured to the bed plate 15 75 in any suitable manner, preferably by threading the ends of the rods thereto. The rods depend from the plate and are provided with adjustable nuts or collars 29 on the free end thereof.

Resiliently yielding members, such as coil springs 30 encompass the rods 28 with one end engaging the lower face of the pin plate or pad 19, and the other ends of the respective springs engage washers 31 which encompass 85 the rods 28 and rest against the nuts 29.

The cylinder is provided with a fill opening 32 above the piston 24, and liquid is supplied thereto from a suitable source through a pipe 33 in which a controlling valve 34 may 90 be arranged. A check valve 35 is also arranged in the pipe to prevent liquid from flowing back into the pipe 33, past the valve 35, due to back pressure of the liquid.

The cylinder 23 is also provided with an 95 opening 36 preferably adjacent the lower end thereof and connected with this opening is a valve casing 37 which has communication with the opening 36 through a suitable opening controlled by a valve 38. This valve is 100 provided with a stem 39 passing through a suitable guide 40. One end of a coil spring 41 rests against a collar 42 secured to the valve stem 39. The other end of the spring engages a collar or abutment 43 carried by a 105 stem 44 which has threaded engagement with an abutment 45 and the stem 44 is provided with an operating handle 46. By rotating the handle 46 the tension of the spring 41 may be varied and thereby the pressure which 110

is necessary to unseat the valve 38 to open the passage 36, may be varied.

The valve casing 37 is also provided with openings 47 which form communication between the valve casing and the passage 36. A valve 48, preferably in the form of an annular member, is provided to close the openings 47. This is accomplished by means of rods 49 which are connected with the valve 48 and pass loosely through the adjacent wall of the valve casing 37. Springs 50 encompass the rods 49 and tend normally to move the valve 48 in a direction to close the passages 47.

The valve casing 37 also has an opening 51 to which is connected a pipe 52 that also has communication with an opening 53 preferably adjacent the top of the cylinder, and on the other side of the piston 24 so that the liquid may circulate from beneath the piston 24, through the pipe 52 to the top side of the piston through the opening 53.

The valves 47 and 48 are disposed between the opening 51 in the casing 37 and the opening 36, the valve 48 being unseated by the pressure of the liquid flowing from the top of the piston so that the liquid will enter the bottom of the cylinder while the valve 48 will be closed by the pressure created by the piston upon the liquid beneath the piston.

30 The valve 38 is set for a predetermined pressure and will be unseated by pressure created upon the liquid under the piston 24 by the action of the piston upon the liquid and when such pressure exceeds the pressure 35 to which the valve 38 is set.

The operation of the machine is as follows. In Figure 1 of the drawing the parts are shown in their normal or initial position, that is with the blank or work holding element 40 17 in position to co-operate with the die 16 to support the work 54, and the piston 24 will be at the limit of its upward stroke in the cylinder 23.

The valve 38 is first set to the pressure 45 which it is desired to establish and the pressure pad or pin plate 19 will be supported by means of the resiliently yielding elements 30.

When the ram 11 descends and the die 12 contacts with the work 54, a further lowering movement of the ram will cause the work to be shaped over the dies. At the same time the pin plate or pad 19 will be depressed by means of the pins 18 against the liquid in the cylinder 23 beneath the piston 24. The 55 lowering movement of the pad 19 will also cause the resiliently yielding elements 30 to be compressed so that energy will be stored therein.

The springs 30 however serve only the 60 purpose of returning or restoring the pad or pressure plate 19 and the energy stored in the springs will be negligible with respect to any resistance pressure created thereby against the lowering movement of the pad 65 or pressure plate 19.

As the piston 24 descends the lowering movement of the pin plate or pad 19 will be yieldingly resisted by the hydraulic pressure created upon the liquid beneath the piston, which pressure will continue until the pressure exceeds the pressure of the spring 41 which holds the valve 38 upon its seat. When the pressure of the valve 38 is exceeded the valve be unseated by the liquid and the liquid will flow into the valve casing 37, 75 thence out of the opening 51, through the pipe 52, into the opening 53 to the top side of the piston 24.

When the ram 11 starts to ascend the pin plate or pad 19 will be raised by the energy 80 stored in the resiliently yielding element 30 and this will raise the piston 24 in the cylinder 22. The liquid on the top side of the piston will be discharged through the opening 53, through the pipe 52 into the valve 85 chamber 37 and from the valve chamber 37 into the openings 49 against the valve 48 to unseat the latter, which will permit the liquid to be discharged through the opening 36 back into the cylinder beneath the 90 piston 24.

The valve 35 will be closed by pressure so as to prevent the liquid from being delivered into the pipe 33 on the upstroke of the piston 24.

With this improved construction it will be manifest that the hydraulic pressure may be controlled at any time during the cycle of operation of the press by adjustment of the tension of the resiliently yielding element 100 41 by adjusting the handle 46.

Furthermore by adjusting the tension of the resiliently yielding element 41 the degree of pressure necessary to unseat the valve 38 may be controlled at will.

It will also be manifest that with this improved construction a predetermined quantity of liquid may be employed and will be circulated from one side to the other side of the piston during the operation of the press. 110

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A pressure cushion for sheet metal presses embodying cylinder and piston members, hydraulic means for resisting the relative movement of said members in one direction, a single conduit for leading the liquid back and forth from one side to the other side of the piston, a valve for closing said conduit for movement of the liquid in one direction therethrough, variably yielding means for holding said valve closed, and an additional valve for closing the same con 130

- duit for movement of the liquid in the last said direction therethrough and operating to permit the liquid to flow through said passage in the opposite direction.
5. A pressure cushion for sheet metal presses embodying cylinder and piston members, hydraulic means for resisting the relative movement of said members in one direction, a single conduit for leading the liquid 70 back and forth from one side to the other side of the piston, oppositely opening valves for controlling the flow of liquid through said single conduit, and means for establishing a predetermined pressure upon one of 75 said valves and against which pressure the valve is adapted to be unseated by the pressure of the liquid thereupon.
3. A pressure cushion for sheet metal presses embodying cylinder and piston members, hydraulic means for resisting the relative movement of said members in one direction, a single conduit for leading the liquid 80 back and forth from one side to the other side of the piston, oppositely opening valves for controlling the flow of liquid through said single conduit, means for establishing a predetermined pressure upon one of 85 said valves and against which pressure the valve is adapted to be unseated by the pressure of the liquid thereupon, and means for varying at will the said predetermined pressure upon the said valve.
4. A self-contained pressure cushion for sheet metal presses embodying cylinder and 90 piston members, said cylinder containing a predetermined supply of liquid, said liquid resisting the relative movement of said members in one direction, a single conduit for leading the liquid back and forth from one 95 side to the other side of the piston, oppositely operating valves for controlling the flow of liquid through said single conduit in opposite directions, and means for establishing and maintaining a predetermined resistance pressure upon one of said valves and against which pressure the valve is adapted to be unseated by the operation of the liquid thereagainst.
5. A self-contained pressure cushion for sheet metal presses embodying cylinder and piston members, said cylinder containing a predetermined supply of liquid, said liquid resisting the relative movement of said members in one direction, a single conduit for leading the liquid back and forth from one 100 side to the other side of the piston, oppositely operating valves for controlling the flow of liquid through said single conduit in opposite directions, means for establishing and maintaining a predetermined resistance pressure upon one of said valves and against which pressure the valve is adapted to be unseated by the operation of the liquid thereagainst.
6. A pressure cushion for sheet metal presses embodying a pressure pad, a cushion for resisting the movement of the pad in one direction, said cushion embodying cylinder and piston members one of which is operatively connected with the said pad, a liquid in the cylinder, a conduit for leading the liquid from one side to the other side of the piston, means for controlling the conduit and operable under a predetermined pressure created upon the liquid by the movement of said pad, and means separate from the cushioning means for supporting the pad, the last said means operating to restore the pad.
7. A pressure cushion for sheet metal 105 presses embodying a pressure pad, an hydraulic cushion for resisting the movement of the pad in one direction, said cushion embodying cylinder and piston members, a by pass for transferring the liquid in the cylinder from one side to the other side of the piston, a valve for controlling the by pass, means creating a predetermined pressure upon said valve and against which pressure the valve is adapted to be opened by the pressure created 110 upon the liquid under the movement of the pressure pad in one direction, and resiliently yielding means separate from the cushioning means for supporting the said pad and serving to restore the pad, the said resiliently yielding means being rendered active to restore the pad by the movement of the pad in one direction.
8. A pressure cushion for sheet metal 115 presses embodying a pressure pad, an hydraulic cushion for resisting the movement of the pad in one direction, said cushion embodying cylinder and piston members, a by pass for transferring the liquid in the cylinder from one side to the other side of the piston, a valve for controlling the by pass, means creating a predetermined pressure upon said valve and against which pressure the valve is adapted to be opened by the pressure created 120 upon the liquid under the movement of the pressure pad in one direction, means for varying at will the pressure of the last said means upon the valve, and resiliently yielding means separate from the cushioning means for supporting the said pad and serving to restore the pad, the said resiliently yielding means being rendered active to restore the pad by the movement of the pad in one direction.
9. A pressure cushion for sheet metal 125 presses embodying a pressure pad, resiliently yielding means separate from the cushioning means for supporting said pad, means for supporting the said means from a stationary part of the press, the first said means operating to restore the pad, an hydraulic cushion for resisting the movement of the pad in one direction, said cushion embodying cylinder and piston members, a conduit for transferring the liquid within the cylinder from one side to the other side of the piston, a pressure 130

controlled valve for controlling the said conduit and for causing a predetermined pressure to be exerted upon the liquid before the conduit will be opened, the said pad being restored entirely by the energy created in said resiliently yielding means when the pad is moved against the said predetermined pressure in the cushion.

10. A pressure cushion for sheet metal presses embodying a pressure pad, hanger members connected with a fixed part of the press, resiliently yielding members separate from the cushioning means and supported by the hanger members and operating upon the 15 pad to support and to restore the same, an hydraulic cushion for resisting the movement of the pad in one direction, said cushion embodying cylinder and piston members relatively movable and one of which last said 20 members is connected with the pad, a conduit for transferring the liquid in the cylinder from one side to the other side of the piston, a valve for controlling said conduit and adapted to be opened by the flow of liquid in 25 one direction through the conduit, and means for creating a predetermined resistance pressure upon the valve against the action of the liquid.

11. A pressure cushion for sheet metal presses embodying a pressure pad, hanger members connected with a fixed part of the press, resiliently yielding members separate from the cushioning means and supported by the hanger members and operating upon the 35 pad to support and to restore the same, an hydraulic cushion for resisting the movement of the pad in one direction, said cushion embodying cylinder and piston members relatively movable and one of which last said 40 members is connected with the pad, a conduit for transferring the liquid in the cylinder from one side to the other side of the piston, a valve for controlling said conduit and adapted to be opened by the flow of liquid in 45 one direction through the conduit, means for creating a predetermined resistance pressure upon the valve against the action of the liquid, and means for varying at will the last recited resistance pressure.

12. A pressure cushion for sheet metal presses embodying a pressure pad, hanger members connected with a fixed part of the press, resiliently yielding members separate from the cushioning means and supported by the hanger members and operating upon the 55 pad to support and to restore the same, an hydraulic cushion for resisting the movement of the pad in one direction, said cushion embodying cylinder and piston members relatively 60 movable and one of which last said members is connected with the pad, said cylinder holding and maintaining a predetermined supply of liquid therein, a conduit for transferring the liquid in the cylinder from one side to the 65 other side of the piston, a valve for control-

ling said conduit and adapted to be opened by the flow of liquid in one direction through the conduit, and means for creating a predetermined resistance pressure upon the valve against the action of the liquid.

13. The combination with a movable support for a blank or work holder, resiliently yielding means separate from the cushioning means for supporting and restoring said support, an hydraulic cushion for resisting the 75 movement of said support and draw ring in one direction, said cushion embodying cylinder and piston members relatively movable and one of which is connected with said support, variable resistance means for controlling the resistance exerted by the cushion element upon the liquid, and means whereby the liquid may be conveyed from the pressure side of the piston to the other side thereof, the resistance of the said resiliently yielding 80 means to the movement of the work holder and support in a direction to create a resistance pressure upon the liquid being negligible.

14. The combination with a movable support for a blank or work holder, resiliently yielding means separate from the cushioning means for supporting and restoring said support, an hydraulic cushion for resisting the movement of said support and draw ring in 95 one direction, said cushion embodying cylinder and piston members relatively movable and one of which is connected with said support, variable resistance means for controlling the resistance exerted by the cushion element upon the liquid, and means whereby the liquid may be conveyed from the pressure side of the piston to the other side thereof, the resistance of the said resiliently yielding means to the movement of the work holder and support in a direction to create a resistance pressure upon the liquid being negligible, the said 100 resiliently yielding means constituting the sole means for restoring the draw ring and support therefor.

15. A pressure cushion for sheet metal presses embodying cylinder and piston members, hydraulic means for resisting the relative movement of said members in one direction, a conduit for leading the liquid back and forth from one side to the other side of the piston, a valve for controlling the movement of the liquid through the conduit, said valve embodying a member having an opening therethrough, a valve to close said opening from one side of the member, there being additional openings through said member, a valve for closing said additional openings from the opposite side of said member, said valves working in opposition to each other and variable yielding means for holding one of the said valves closed.

16. A pressure cushion for sheet metal presses embodying cylinder and piston members, hydraulic means for resisting the rela-

tive movement of said members in one direction, a conduit for leading the liquid back and forth from one side to the other side of the piston, a valve for controlling the movement of the liquid through the conduit, said valve embodying a member having an opening therethrough, a valve to close said opening from one side of the member, there being additional openings through said member, a 10 valve for closing said additional openings

from the opposite side of said member, said valves working in opposition to each other, springs individual to the valves for respectively seating them, and means for varying at will the stress of one of the springs upon its 15 respective valve.

In testimony whereof I have signed my name to this specification, on this 29th day of March, A. D. 1927.

FREDRICH J. RODE.
